UNITED STATES PATENT OFFICE.

JOHN R. STENECK, OF OAK PARK, ILLINOIS; ASSIGNOR TO ILLINOIS MALLEABLE IRON COMPANY, OF CHICAGO, ILLINOIS, A CORPORATION OF ILLINOIS.

UNION.

No. 883,122.

Specification of Letters Patent. Patented March 24, 1908.

Application filed September 23, 1907. Serial No. 394,199.

To all whom it may concern:

Be it known that I, JOHN R. STENECK, a citizen of the United States, residing at Oak Park, in the county of Cook and State of Illinois, have invented a new and useful improvement in Unions, of which the following is a specification.

Figure 1 is a central longitudinal section through my improved union; Fig. 2 is a transverse section in a line 2 of Fig. 1; and Fig. 3 is a central longitudinal section through a modified form of spud.

Referring to the drawings, A is the tail-piece of my improved union, the same being constructed of brass and having at its upper end a seat a, roughly conical in form, and having preferably a surface which is slightly convex in cross-section, as illustrated. The upper portion of the tail-piece is provided with a shoulder a¹, as is usual in union construction.

B is the nut or ring of my improved union, the same being constructed of iron, and having at its lower end an inwardly-projecting flange b which engages with the shoulder a¹ aforesaid. The spud of my improved union is screwed into the ring in the usual way and the same comprises two portions C, C¹. The portion C of the union is of iron and has at its lower end a seat of internally conical form which engages with the seat a on the upper end of the tail-piece A. The member C of the spud also has a laterally-projecting ring or flange c which is provided with a series of notches, as illustrated in Fig. 2.

In the form of spud illustrated in Fig. 1, the portion C¹ of the spud, which is of brass, is cast on the portion c and is held permanently in position against any possibility of movement by fitting tightly the flange c and the notches therein. In the form of spud illustrated in Fig. 3, the two portions thereof are indicated by the characters C^a and C^a¹. It is to be noted that in this form of construction the flange is omitted from the member C^a and the portion C^a¹ is screwed up upon the portion C^a, being held in position by a small locking-pin c^a, or by any other desirable means. Either of these constructions

is particularly desirable by reason of the fact that all the points of contact between the three portions of the union are brass to iron, so that there is no possibility of any one of the points of contact becoming so corroded as to make the union stick, whereby the separation of the parts becomes difficult when it is desired to be brought about. Thus the tail-piece and spud contact with brass to iron meeting faces, the brass outer annulus upon the spud contacts with the iron of the nut or ring and the brass shoulder upon the tail-piece contacts with the iron of the ring or nut. Thus a construction is produced which is superior in operation and mechanical effect to any union which has heretofore been produced and the amount of the more expensive material, i. e., brass in the construction is not such as to make the union unduly expensive.

I realize that considerable variation is possible in the details of this construction without departing from the spirit of my invention; therefore, I do not intend to limit myself to the specific form herein shown and described.

By the term "brass" in this specification and in the following claims, I mean, of course, any metal, brass being the most common example of such metals, which, when brought into contact with iron, will not form therewith a joint which will stick by reason of corrosion. In practice, brass, bronze or copper will doubtless be used for the parts described as of brass.

What I claim as new, and desire to secure by Letters Patent, is—

1. In a device of the class described, the combination with an iron nut, of an iron spud having an iron seat and a brass annulus screw-threaded to engage the nut, and a tail-piece having a seat and shoulder of brass whereby non-corrodible joints are secured at all three contact points.

2. The combination with an iron nut, of an iron spud having an iron seat and a brass screw-threaded annulus secured to and forming part of the spud and engaging the nut, and a brass tail-piece having a seat to engage

the iron seat of the spud and a shoulder to engage the nut.

3. In a device of the class described, a spud comprising two portions, an inner iron portion having a seat and an outer screw-threaded portion of brass, an iron nut engaging the threads upon said outer portion of

the spud, and a brass tail-piece engaging the nut and having a seat co-operating with the seat upon the spud.

JOHN R. STENECK
